JEWELRY DISPLAY STAND

Herbert H. Longen, 3207 67th Ave. N.,
Brooklyn Center, Minn. 55429

Filed Oct. 29, 1975, Ser. No. 626,717

Term of patent 3½ years

Int. Cl. D20—02

U.S. Cl. D6—28

FIG. 1

FIG. 3

FIG. 4

FIG. 2

FIG. 1 is a view in perspective as seen from the top and two sides of a jewelry display stand showing my new design;

FIG. 2 is a view in top plan thereof;

FIG. 3 is a view in side elevation as seen from bottom to top of FIG. 2, the side opposite that shown being substantially a mirror image; and

FIG. 4 is a view in side elevation as seen from left to right of FIG. 2, the side opposite that shown being substantially a mirror image.

I claim:

The ornamental design for a jewelry display stand, substantially as shown and described.
